UNITED STATES PATENT OFFICE.

ARTHUR WAYNE CLARK, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

FUMIGATOR.

1,413,321.

Specification of Letters Patent. Patented Apr. 18, 1922.

Application filed June 24, 1920. Serial No. 391,293.

To all whom it may concern:

Be it known that I, ARTHUR WAYNE CLARK, a citizen of the United States, residing at New Brunswick, in the county of 5 Middlesex and State of New Jersey, have invented certain new and useful Improvements in Fumigators, of which the following is a specification.

This invention relates to a portable fumigator in which disinfecting material is volatilized under the application of heat.

The improved structure comprises a substantially self contained unit which embodies a stand or support, a heater, and a container 15 for disinfecting material. The stand has openings to maintain combustion and to properly direct the flame or heat about the container. The latter is equipped with a flange whereby it is supported upon the upper end of the stand, the flange, serving as 20 a shield or deflector, to prevent the flame of the heater from igniting the vapor issuing from the container outlet.

In the drawings:—

Fig. 1 is an elevation, partly in section, showing the fumigator assembled.

Fig. 2 is a detail of the container, the body and cap being separated.

Fig. 3 is a perspective view of the stand or support.

The improved fumigator comprises a generally cylindrical stand or support 1 having a bottom 2, and open at the top. The stand is provided near the bottom with a series 35 of air intake openings 3, and near its top, with openings 4. A heating means 5, here shown as a can containing solid alcohol, so called, is adapted to be placed within the support, resting on the bottom thereof, the 40 openings 3 providing sufficient air for combustion. Obviously any appropriate type of heating means may be employed, the invention not being concerned with this particular detail, so long as sufficient heat is 45 generated within the support.

The container is in the form of a can body

6, filled with, for example, paraformaldehyde, and having a tight fitting cover 7, with a funnel-like vapor outlet 8. The cover has a lateral flange 9 formed with an annular depending rib 10.

The container is applied to the stand with the flange 9 resting upon the upper edge thereof, the rib 10 acting as a distance element. By this means the container is spaced from the support so that the flame or hot products from the heater 5 may directly reach a comparatively large surface of the container and more effectively and quickly volatilize the contents thereof. The openings 4 in the support provide for the escape of the products of combustion, and it frequently happens that flame from the heater will reach through these openings. It is of importance that this flame be prevented from igniting the vapor issuing from the outlet 8, and it is for the deflection of such flame from the vapor that the flange 9 is provided. This flange projects beyond the support to an extent providing for its effective service 70 as a complete barrier to the flame, and hence all possibility of igniting the disinfecting material.

Having described my invention, I claim:—

A fumigator including a support having 75 openings near the upper and lower edges thereof, a container adapted to be arranged within the upper end of the support and having a diameter less than that of the support, and a cover for said container having 80 an outlet and adapted to engage the container with sufficient friction to support the container from the cap, said cap having a rib formation at the lower end thereof of an exterior dimension corresponding to the 85 interior diameter of the support, whereby said rib serves to center the container within and spaced from the wall of the support to expose the full surface of such container.

In testimony whereof I affix my signature. 90

ARTHUR WAYNE CLARK.
